[57] CLAIM

The ornamental design for a food serving tray, as shown and described.

DESCRIPTION

FIG. 1 is a top plan view of a food serving tray showing my new design;

FIG. 2 is a sectional view taken along the line 2—2 of FIG. 1;

FIG. 3 is a bottom plan view;

FIG. 4 is a right side elevational view thereof, the left side elevational view being identical to FIG. 4.

FIG. 1

FIG. 4

FIG. 2

FIG. 3
